FOLDING BERTH FOR SLEEPING CARS
AND SUPPORTING AND LOCKING
MEANS THEREFORCharles L. Fike, Ardmore, Pa., assignor to The
Budd Company, Philadelphia, Pa., a corpora-
tion of Pennsylvania

Application April 15, 1949; Serial No. 87,606

4 Claims. (Cl. 105—321)

1

The invention relates to railway sleeping cars, and particularly to such cars having rooms equipped with berths folding about an axis adjacent one margin thereof to a stowed position against a room wall and movable from such stowed to a horizontal use position extending across the room floor.

The invention is particularly concerned with the means for supporting and latching the free end of the berth remote from its pivoted end in the down or use position. It finds use primarily in rooms where one corner of the free end of the berth is adjacent a fixed room wall so it can be latched thereto, and where the opposite corner projects over a space having no fixed room wall adjacent thereto, so that means independent of the room walls are required to support that corner of the berth.

It is an objection of the invention to provide a simplified means for supporting and latching the free end of the berth in the down or horizontal use position.

Such means may comprise a folding leg for supporting the corner of the berth remote from a fixed wall of the room, and latching means for latching the other corner to the adjacent fixed wall and connections between said latching means and the folding leg whereby the latch is automatically released when the leg is folded.

The above object and other and further objects and advantages and the manner in which they are attained will become fully apparent from the following detailed description when read in connection with the accompanying drawings forming a part of this specification.

In the drawings,

Figure 1 is a sectional plan view, parts being shown more or less diagrammatically, of a portion of a railway sleeping car showing a room and berth arrangement to which the invention has been applied; the section being taken substantially along the line 1—1 of Fig. 2;

Figure 2 is a longitudinal vertical sectional view of said car portion, the section being taken substantially along the line 2—2 of Fig. 1;

Figure 3 is a fragmentary side elevational view on an enlarged scale, of the free or foot end of the berth shown extending longitudinally in Fig. 1, this view showing the supporting leg in folded condition;

Figure 4 is a view similar to Fig. 3 showing the supporting leg in extended or operative position, as shown at the bottom center of Fig. 2;

Figure 5 is a transverse vertical sectional view

through the berth frame and the adjacent car side wall, the section being taken substantially along the line 5—5 of Fig. 3;

Figure 5a is a detail sectional view showing the latch and latch actuator rod in a different position from that shown in Fig. 5; this being the position the parts assume when the supporting leg is moved to the operative position shown in Fig. 4;

Figure 6 is a detail plan view of the corner of the berth supported by the leg, parts being broken away and shown in section;

Figure 7 is a detail sectional view taken substantially along the line 7—7 of Fig. 6;

Figure 8 is a detail sectional view taken substantially along the line 8—8 of Fig. 4; and

Figure 9 is a detail sectional view taken along the line 9—9 of Fig. 4.

The invention has been shown applied to a railway sleeping car of the type shown in Patent #2,462,027 to G. K. Murphy, issued February 15, 1949 and entitled Railway Sleeping Car, although it will be understood that it will find application in other relations or wherever a folding berth pivoted adjacent one margin thereof has its free margin, when extended to horizontal use position disposed with one corner thereof adjacent a fixed wall of a room in which it is mounted and its opposite corner remote from a fixed wall.

The car and room arrangement to which the invention is applied will now be briefly described so that the background of the invention may be made apparent.

Referring to Figures 1 and 2, the car side walls are designated 10 and 11, the roof, by 12, and the floor by 13. An aisle wall, as 14, divides the space between the car side walls into a side aisle, as 15, and a space for rooms disposed between the car side wall 10 and the aisle wall 14.

The space for rooms is divided by fixed transverse walls 16 and 17 and a collapsible transverse wall 18 into a pair of adjoining rooms designated generally by reference characters A and B. The room arrangement may be continued throughout the length of the car or for any desired part of its length and with the pairs of rooms A and B alternately reversely arranged. The adjoining rooms A and B separated by the collapsible partition, as 18, may be thrown together into one large room, by folding the partition as shown in full lines in Figure 1. Access to the room B may be had from the aisle through a doorway and sliding door 19, and when the rooms are thrown

together, this doorway and door also provide access to the room A.

However, when the rooms are separated by the closing of the collapsible partition as indicated by the dotted lines in Fig. 1, access to the room A may be through a doorway in the offset portion 20 of the aisle wall, and through a passageway 21 whose walls are indicated by 22, 22, and a doorway in the inclined wall 23, all as clearly disclosed in the hereinbefore referred to patent. Enclosed toilet compartments for the rooms A and B may be arranged as diagrammatically indicated at 24 along the aisle side of the rooms and extending between the door and doorway 19 and the offset 20.

Each of the rooms A and B may be made up either as a sitting room or as a bedroom. Room B, when made up as a bedroom as shown, has an upper berth 25 and a lower berth 26 extending transversely of the room along the transverse wall 16. To convert it into a sitting room, the upper and lower berths are folded against the wall 16 in a manner well understood in the art. The lower berth then forms the back of a sofa whose seat is indicated at 27.

Room A, when made up as a bedroom, as shown centrally of these figures, has an upper longitudinally extending berth 28 and a lower longitudinally extending berth 29. The upper berth 28 may be moved through guiding grooves 30 on the transverse wall 17 and on a fixed portion 31 of the collapsible wall 18 and coacting roller pins 32 on the ends of the berth, see Fig. 2, upwardly and laterally to a stowed position adjacent the aisle.

The lower berth 29, when moved to the stowed position, is guided by pins 33 and coacting channels on the room walls (not shown) while supported by the links 34, so as to swing about a floating axis adjacent the head end of the bed to a vertical stowed position flanking the wall 17 as shown at the left of Figures 1 and 2. Counterbalance springs, as 35, facilitate this movement. When in this position, a seat back 36, secured to the bottom of the berth is brought into cooperative relation with a seat 37. The seat 37 may be slid forward, as shown centrally of Fig. 2, when the berth is lowered to the use position. An additional folding chair 38 provided in room A may likewise fold under the berth 29 when the latter is in the horizontal use position.

It will be seen from the foregoing, that the free or foot end of the berth 29, when in the use position, has one corner thereof located adjacent the fixed side wall 10 of the car and the opposite corner at said end disposed inwardly of the room and remote from a fixed wall of the room.

Since the invention is primarily concerned with the support and latching in place of this end of the bed, such support and latching means will now be described by reference to the detail Figs. 3 to 9, inclusive.

The berth 29 comprises a shallow open box frame for receiving the springs, mattress and bed clothes.

This frame has a bottom wall 39 and side walls 40 and 41 and end walls, as 42. The side and end walls are preferably reinforced by inner rails 43 flanged in their margins as at 44 and 45 and secured through said flanges, respectively, to the adjacent side and end walls 40, 41 and 42 and the bottom 39 of the berth frame.

The side wall 41 is offset in its lower margin to provide a longitudinally extending angular recess 46, the purpose of which will later appear.

The car side wall 10 carries on its inner side panel 47 a usual form of snap latch 48 pivoted at 49 on a bracket 50 secured to the side panel 47, the latch being constantly urged away from the panel 47 by a coil spring 51. It is limited in its movement under the action of the spring 51 by a stop abutment 52. On the side wall 40 of the berth, which is disposed in closely spaced parallel relation to the panel 47, is provided a latching recess or keeper 53 into which the latch 48 is automatically snapped; when the berth is swung down to use position, to occupy the position shown in Fig. 5a, and so lock the berth in the down position. A suitable stop (not shown) on the panel 47 limits the downward movement of this corner of the berth, and the latch locks it down on this stop.

To support the opposite corner of this free end of the berth, a foldable leg 54 is provided, this leg being rigidly secured to a shaft 55 mounted to rotate in spaced brackets 56, 56 secured to the end rail 43. Endwise movement of the shaft 55 is prevented by collars 57 rigidly secured thereto and bearing against the adjacent faces of the brackets 56, 56, see Fig. 6.

When extended, as shown in Fig. 4, the leg supports the adjacent corner of the berth from the floor 13. It is locked in this extended position by a brace 57 pivoted at 58 to the berth frame and at 59 to the leg. This brace is preferably made in two parts 57a, 57b which have their adjacent ends in overlapping relation, see Fig. 8, and guided by a sleeve 60 surrounding them and rigidly secured to one of the parts, as 57b. A spring catch, as 61, secured to the sleeve 60 automatically springs over the end of the other part, as 57a, to hold the brace extended. This spring catch is so designed that it may be cammed aside, if sufficient force is applied to the leg, so that the brace may be collapsed and the leg may be moved to the folded position shown in Fig. 3, where both it and the brace 57 are received within the recess 46 of the bed frame. To secure the leg in this position, a wedge-shaped projection 62 adjacent the free end of the leg is adapted to snap into a spring catch 63 on the berth frame. This catch can be released by merely pulling down on the folded leg with sufficient force.

According to the invention, the latch 48 is arranged to be released by the folding movement of the leg 54. To this end, a push rod 64, adjustable in length, is mounted to slide transversely of the berth with one end thereof disposed in the latching recess 53 and its opposite end in the recess 46. A collar 65 on the rod limits its movement into the recess 46 and the rod is normally moved laterally, (toward the left, Fig. 5) to the limit allowed by this collar by a coil spring 66, reacting between a collar 67 on the rod and the bed frame, see Fig. 5. This rod 64 is so located with respect to the pivot of the leg and a cam 68 secured to the leg that, when the leg is moved to folded position as shown in Figs. 3 and 5, the cam engages the adjacent end of the rod 64 and forces it laterally from the dotted position indicated at the left of Fig. 5 to the full line position shown in said figure. The opposite end of the rod, in this movement, forces the latch 48 out of its locking recess 53, thereby releasing the berth to permit it to be moved to the stowed position. In bringing the berth from the stowed position to the use position, the leg is normally swung downwardly toward its operative position before the berth is down, so that the push rod is freed to the action of its spring 66 and occupies

the position shown in Fig. 5a, where the latch 48 is free to spring into latching engagement with the recess 53 as soon as the berth reaches its down position. At the same time the fully extended leg is locked by its brace in the vertical position shown in Fig. 4 to support its corner of the berth.

The operation of the device has been made clear by the foregoing detailed description so that further description would seem unnecessary.

While a specific embodiment of the invention has been described in detail, it will be understood that changes and modifications may be made by those skilled in the art without departing from the spirit and scope of the invention.

What is claimed is:

1. In combination, a sleeping car room defined by spaced longitudinally extending car side and aisle walls and spaced transverse walls interconnecting with said side and aisle walls, a berth pivoted adjacent one of said transverse walls and movable between a stowed position flanking said wall and a horizontal use position, a collapsible leg on the berth for supporting one corner of the free end of the berth, and means for locking the opposite corner to an adjacent longitudinal wall, said means being automatically rendered operative by the extension of the collapsible leg to its supporting position.

2. In combination, a sleeping car room defined in part by longitudinally and transversely extending walls, a berth pivoted adjacent one of said walls and movable between a stowed position flanking said wall and a horizontal use position with one corner of its free end adjacent said other wall, a collapsible leg on the berth for supporting the opposite corner of said free end of the berth, and a latch adjacent said one corner for locking it to the adjacent wall, and means for automatically moving said latch to release po- 40

sition when the leg is moved to collapsed condition while the berth is in the horizontal use position.

3. In combination, a berth pivoted adjacent one end thereof and movable about said pivot from a vertical stowed position to a horizontal use position, a spring-pressed latch for locking one corner of the free end of the berth in the use position, a supporting leg pivoted to the opposite corner of said free end, said leg being collapsible to lie folded alongside the berth, and means operatively connecting said leg to said latch so as to free the latch to its latching function when the leg is moved from its collapsed position toward its use position but so as to move the latch to inoperative position when the leg is moved from its use to its collapsed position.

4. In combination, a berth pivoted adjacent one end thereof and movable about said pivot from a vertical stowed position to a horizontal use position, a spring-pressed latch for locking one corner of the free end of the berth in its use position, a collapsible supporting leg pivotally supported on the berth adjacent the opposite corner of said free end and supporting said berth when extended, a transversely extending operating rod on the berth having one end thereof in position for imparting release movement to the latch and normally biased to cause its opposite end to project into the path of movement of the leg when said leg is moved to its collapsed position, and a cam means carried by the leg and arranged to engage the adjacent end of the rod, when the leg is moved to its collapsed position, to move the rod endwise against its biasing means and thereby operate the latch to its release position when the berth is locked in the use position.

CHARLES L. FIKE.
